ADJUSTABLE COUNTERSINK OR THE LIKE

Fred Hotchner, Los Angeles, Calif.

Application January 21, 1943, Serial No. 473,145

6 Claims. (Cl. 77—73.5)

This invention relates to a countersink or the like having removable bits which may be quickly adjusted so as to countersink holes to any of a wide range of angles, and which may be quickly removed for resharpening or replacement by other bits ground for various special purposes such as spot facing, end milling, reaming or counterboring. For general shop use the tool is suitable as a common countersink with cutting edges extending close to the tool axis and capable of chamfering holes of any size up to its extreme capacity for any given angle. It may as well be used as a pilot countersink for specific diameters of holes by the insertion of bits ground for the purpose.

It is an object hereof to produce a simple, rugged tool which may be manufactured to a high degree of tolerance at moderate cost, which will retain its accuracy over a practically indefinite life, and be capable of accurate setting and adjustment by mechanics of ordinary skill.

As embodied in an adjustable countersink, in which form the invention is shown in detail in the accompanying drawing, it is an object to provide a tool, which as a single tool with a selection of bits in a shop, will take the place of not only the variety of countersinks ordinarily kept on hand to chamfer holes at different angles, but serve as a general utility tool of numerous applications.

It is a further object to produce a tool having means to hold the bits by broad surface contact firmly wedged in cavities without any chance of play, and backed up close to the cutting edges by substantial masses of metal delivering driving force through the shortest dimension of the bits to the cut surface, in order to minimize the strain on the bits and any tendency to chatter by resilience in any part of the tool.

Another object is to produce a tool of the character described which, whether used as a pilot tool or otherwise will have a properly contoured cutting edge with ample chip clearance and substantial backing up to the innermost diameter of the work, and further capable of repeated resharpening without detracting from these important features.

An item of first importance with all cutting tools of the class herein concerned is the facility with which the angle of the cutting edges may be controlled and checked. It is an object hereof to produce a tool the blades of which may be set by direct gauging with a protractor to an accurate visual control and as readily checked during use with loosening any parts.

Additional objects of the invention will be ap-

parent in the following specification taken together with the drawing in which I show my tool in certain preferred embodiments thereof. It is to be understood however, that this invention is not limited to the forms shown but may be variously embodied in a cutting tool in various modifications of its different features within the purview of the appended claims, the terms of which are to be read as embracing all substantial equivalents thereof.

In the drawing the same reference numeral indicates the same or the equivalent part throughout.

Figure 1 is an elevation of a tool provided with straight edge bits without pilots. The bits are shown set at 45° as an average angle of cut for general use. Figure 2 is an end view of the tool in conventional projection from Figure 1.

Figure 3 is a sectional view of the tool from the same direction of view as that of Figure 1 and taken as indicated by the section line 3—3 in Figure 2.

Figures 4 and 5 are sectional views of the same taken as indicated by the section lines 4—4 and 5—5 in Figure 1.

In Figure 6 I show a cross section through the bit and the immediately associated elements of the holder showing the manner in which the bit is pressed home in its recess in the head. The axis of the bit is shown by the line X—X and in broken lines a continuation of the solid of revolution of which the bit is a segment. Taken in connection with the three axes similarly marked shown in Figure 2, and the line X'—X' in Figure 1, representing the plane in which these axes lie, the degree of freedom of the bits is defined. This view is taken along section line 6—6 in Figure 3.

Figure 7 is a perspective view of the bit showing by broken lines a continuation of the solid of revolution of which it is a segment and also showing the bit axis X—X.

Figures 8 and 9 illustrate the setting of the bits to different angles of countersink.

Figures 10 to 13 show the contouring of special bits for various special purposes and especially the contouring of bits for pilot control operations.

Figure 14 is a sectional view of a modified form of the tool in which the holder is a single piece having a central locking rod.

The tool comprises a holder, indicated by numeral 1, a plurality of bits 3, and means in the holder to restrain the bit to a certain degree of freedom for adjustment and lock them in a given position within such restraint for cutting service.

Each bit is a segment of a solid of revolution having a cutting edge along a chord of the circle of one side of this solid, and is retained in the holder in a cavity having a pair of opposing main walls of similar contour.

As seen in the perspective view of Figure 7 and the cross section of Figure 6 this solid of revolution is a disk having one flat and one concave side. The bit therefore has one flat side, indicated by numeral 6. The cutting edge 7 is along a chord of this side. The other side 5 of the bit converges to the side 6 from the rim 10 toward the axis X—X. The clearance surface 8 is ground backward away from the cutting edge, being somewhat steeper toward the corner 9 which is the central edge of the bit as it is set in the holder. For the sake of cutting edge formation the rim 10 may be perpendicular to the side 6. However, in designing tools favor may be given the feature of the contact between the bits and the locking wedge at the expense of other features of the tool if found desirable.

Various constructions may be employed in the holder. The most simple construction is that shown in the drawing in which the bits are held in recesses cut into the solid material of the holder, the walls of the recesses being complementary to the surfaces of the bits. Thus, since the sides of the bits converge toward the bit axes they cannot move out of the recesses radially but must be rotated around their axes to admit, adjust or remove them from the holder. To lock them in position means are provided to force them outward against the walls of the recesses thus bringing into play a frictional engagement which holds them firmly in position against all working forces. Furthermore the mass of the bits and the holder head are combined as one solid body effective close to the bit heels to back up the cutting edge with the minimum of stress in the bits. This makes it quite practicable to use the more brittle cutting materials such as the carbides which take heavy cuts at high speed but do not withstand internal stress when unsupported against the reaction of the work.

In Figure 6 a section through the bit is shown, the remainder of the solid of revolution of which it is a part being shown in broken lines. The bit can only move, when in the holder, by rotation around the axis X—X as shown. The wall of the recess contacting side 5 of the bit is indicated by numeral 12 and the edge of this wall by 13 in Figures 1 and 2. Likewise the opposite wall contacting side 6 of the bit is indicated by 14 and its edge by 15 in Figures 1 and 2. The recesses may be cut to a high degree of accuracy on a milling machine so that the bits will, if manufactured to a uniform size, fit with but a few thousandths of an inch play and be freely interchangeable in the different recesses. The edge 10 of the bit will be pressed away from its mating surface in the recess a very slight amount, usually insufficient to be noticeable, and hence no space is shown between them in the drawing.

In Figure 1 the line X'—X' indicates the plane in which all of the axes of the bits lie. In Figure 2 the axes of the bits are shown tangent to a circle in broken line. This defines the bits as similarly spaced lengthwise with the tool axis Y—Y, to have the same lead into work, and parallel thereto. It will be seen that the face 6 of each bit is in line with the tool axis. Therefore a protractor laid along the side of the holder will give a direct gauge of the bit angle, affording a very convenient means of setting the tool.

In Figures 2 and 3 we see that the points 16 of the bits come very close to the tool center so that the tool may be used in all sizes of holes from a very small size up to its maximum capacity. In Figures 8 and 9 it is shown that the variation of the minimum size of hole is very slight even for extreme adjustments of the tool.

To lock the bits in position I provide a wedge member and means to press it forcefully against the edges 29 of the bits. The wedge should be free to shift radially so that it will equalize the pressure between the bits. To carry this feature out, the preferred construction is to drill a hole through the holder from the opposite end, insert the wedge and back it up with a screw. In the tool of Figures 1 to 13 the holder is in two pieces. The head has the hole 18 drilled into it until it opens up through the recesses sufficient to allow a small portion of the back of each bit to be exposed in the hole as indicated by 19. The end of the hole is tapped at 20 to receive the threaded end 21 of the shank 22. The holder is cut to a hexagon at 23 and the shank carries a hexagon shoulder at 24 for the reception of the jaws of wrenches to tighten the tool.

The end of the shank has a center hole 27. The wedge plug 25 has a pointed end 26 fitting into this hole. The plug is slightly less in diameter than the bore of the hole so that it can rock sufficient to equalize the pressure between the bits. The end 28 is contoured to fit the edges 29 of the bits. As will be seen in Figure 6, if this edge is a sharp corner, the contact between bit and wedge will be a line contact. If the bit be made of brittle material it may be necessary to shape the bit edges to provide a surface contact with the wedges at a slight expense to the feature of a well pointed tool to work in small holes.

In setting the tool, the wedge is loosened just sufficient to permit the bits to be moved by lightly tapping on one end or the other of the back of the clearance surface. By means of a protractor along the edge of the holder the angle is gauged until all of the bits are at the desired angle and then the wedge is tightened by screwing up the shank. Another convenient method of setting the tool is to make a taper gauge by turning out a block of metal to the desired angle and setting the bits by holding the tool in its proper position in the hole, pressing the bits against the tapered surfaces and tightening them in place.

The bits may be given any desired rake by grinding backward on the surface 6 and the clearance modified according to the usual practices, advantage being taken of the ample chip clearance space to attain a better tool formation at the point of the tool than that which may be had with the fixed countersinks of the prior art. It is particularly to be noted that the invention is not limited to the particular concave radial section of bit which I have shown with the correspondingly tapered slot section. I have shown this as my preferred contour because the wedging of bits of this section into the recess shown has the effect of forming a solid mass of each bit and the boss 17 behind it up to the heel of the cutting edge, forming a very desirable tool feature. Various other contours, such as L slots or T slots may be used for special purposes.

Figures 8 and 9 show two extreme angles for countersinking. It is seen that the bits are well backed up over the extent of the cutting edges where the heaviest service is met for the range of

angles met in general shop practice. It is obvious that for special service the contour of the holder may be modified to increase this backing at one region or the other and that the material of the head in front of the faces of the bits may be cut away to improve chip clearance if desired.

The provision of pilots for countersinking or spot facing is readily had with my tool. Figures 10 and 11 show bits ground with pilot shoulders. 35. In Figure 10 a pilot countersink is shown and in Figure 11 a counterbore. In these views and also in Figures 12 and 13 I have shown in broken lines the position taken by the bits in their sweep around the tool axis for the sake of clarity. It will be seen that these pilot shoulders are the equivalent for all practical purposes of a solid pilot pin. The edges 36, obviously must be ground concentric with the tool axis. The cutting edges are indicated by 38 and the clearance by broken lines. It will be seen at 39 that the clearance undercut the shoulder to permit of grinding the edge up to the pilot. A taper entering edge may be ground at 37 to any angle desired.

Figure 12 shows the adaptation of the tool by suitable bits as an end mill and Figure 13 as reamer.

Figure 14 shows a construction in which the holder is in one piece with a central locking rod. The holder 40 has recesses cut in the head as described above and the hole 42 is drilled up to and opening into these recesses. The locking rod 41 is threaded in the threaded end 43 of the holder and has a hexagon head 44 for tightening with a wrench. The opposite end 45 of the rod is contoured to fit the edges of the bit. The rod should be slightly smaller in diameter than the bore of the hole and be resilient enough to equalize the pressure between the bits by springing the maximum displacement from the axis which any inequality in construction might produce.

The novel features of this invention may be applied to cutting tools of various types other than the general class embracing those specifically described above.

The term "concave" descriptive of the contour of the bits as used in the claims is embracive of special formations such as those presented by T or L sections.

Having thus described my invention, what I claim is:

1. A countersink comprising: an arbor having a plurality of cavities opening to the leading end thereof, each of which cavities has a pair of opposing side walls and an arcuate rim wall all concentric and symmetric around an axial line, all of which axial lines are tangent to a circle of radius approximating that of the cavity rim walls, said circle lying in a plane perpendicular to the arbor axis being concentric with the same and slightly forward of the leading end of the arbor, one side wall of each cavity being convergent at least in part toward the other wall from the rim toward the cavity axis so that a solid of revolution of surfaces complementary to the said cavity walls may turn in any of said cavities around the cavity axis but may not move radially outward therefrom, the leading one of the walls of each of said cavities in the direction in which the tool turns in use being parallel to and radiating from the arbor axis, there being an axial opening in said arbor from the trailing end thereof to and opening into each of said cavities through the rim walls thereof, a bit in each of said cavities comprising a segmentary portion of

a solid of revolution of surfaces complementary to the cavity walls and having a working edge along a chord of the side corresponding to the leading wall above described of the respective cavities, a wedge member in said axial opening in said arbor bearing on the rims of said bits where they are exposed through the rim wall openings of their respective cavities, and means to force said wedge member against said bits to lock them in their set positions.

2. A device as set forth in claim 1 in which the cavities and the bits are respectively three in number and said wedge member equalizes its pressure between the bits to automatically compensate for irregularities in construction and those caused by wear and foreign matter.

3. A countersink comprising: an arbor having a plurality of cavities opening to the leading end thereof, each of which cavities has a pair of opposing side walls and an arcuate rim wall all concentric and symmetric around an axial line, all of which axial lines are tangent to a circle of radius approximating that of the cavity rim walls, said circle lying in a plane perpendicular

20 to the arbor axis being concentric with the same and slightly forward of the leading end of the arbor, one side wall of each cavity being convergent at least in part toward the other wall from the rim toward the cavity axis so that a solid of revolution of surfaces complementary to the said cavity walls may turn in any of said cavities around the cavity axis but may not move radially outward therefrom, the leading one of the walls of each of said cavities in the direction

30 in which the tool turns in use being parallel to and radiating from the arbor axis, there being an axial opening in said arbor from the trailing end thereof to and opening into each of said cavities through the rim walls thereof, a bit in each of said cavities comprising a segmentary portion of a solid of revolution of surfaces complementary to the cavity walls and having a working edge along a chord of the side corresponding to the leading cavity wall of the respective cavities,

35 and a locking member for said bits extending through said axial opening in said arbor bearing on the rims of said bits where they are exposed through the rim walls of their respective cavities and adapted to be driven thereagainst to lock the bits in their set positions.

4. A device as set forth in claim 3 in which the cavities and the bits are respectively three in number and said locking member is adapted to equalize the pressure from one bit to the other to compensate for irregularities in its bearing thereagainst.

5. A countersink comprising: an arbor having a plurality of cavities opening to the leading end thereof, each of which cavities has a pair of opposing side walls and an arcuate rim wall all concentric and symmetric around an axial line, all of which axial lines are tangent to a circle lying in a plane perpendicular to the arbor axis and slightly forward of the leading end of the arbor, one side wall of each cavity being convergent at least in part toward the other wall from the rim toward the cavity axis so that a solid of revolution of surfaces complementary to the said cavity walls may turn in any of said cavities around the cavity axis but may not move radially outward therefrom, there being an axial opening in said arbor from the trailing end thereof to and opening into each of said cavities through the rim walls thereof, a bit in each of said cavities com-

prising a segmentary portion of a solid of revolution of surfaces complementary to the cavity walls and having a working edge lying along a chord of one side, and a locking member extending through said axial opening in said arbor bearing on the rims of said bits where they are exposed through the rim wall openings of their

respective cavities and adapted to be driven thereagainst to lock the bits in their set positions.

6. A device as set forth in claim 5 in which the cavities and bits are respectively three in number and said locking member equalizes its pressure from one bit to the other two.

FRED HOTCHNER.
